CLAIM

The ornamental design for a light for attachment to a remote control, as shown and described.

DESCRIPTION

FIGS. 1-5 are perspective views of an illumination device for remote control devices showing our new design;

FIG. 6 is a front view of the illumination device for remote control devices of FIGS. 1-5.

FIG. 7 is a top view of the illumination device for remote control devices of FIGS. 1-5.

FIG. 8 is a bottom view of the illumination device for remote control devices of FIGS. 1-5.

FIG. 9 is an elevational end view of the illumination device for remote control devices from the left-hand side of FIG. 6; and,

FIG. 10 is an elevational end view of the illumination device for remote control devices taken from the right-hand side of FIG. 6.
